UNITED STATES PATENT OFFICE.

HENRY H. WAIT, OF CHICAGO, ILLINOIS, ASSIGNOR TO THE WESTERN ELECTRIC COMPANY, OF SAME PLACE.

DESIGN FOR A MOTOR-FRAME.

SPECIFICATION forming part of Design No. 30,785, dated May 16, 1899.

Application filed April 12, 1899. Serial No. 712,810. Term of patent 7 years.

To all whom it may concern:

Be it known that I, HENRY H. WAIT, a citizen of the United States, residing at Chicago, in the county of Cook and State of Illinois, have invented and produced a new and original Design for Motor-Frames, (Case 14,) of which the following is a specification, reference being had to the accompanying drawings, forming a part thereof.

Figure 1 is a view in elevation of a motor-frame, showing my new design. Fig. 2 is vertical sectional view taken on line $x-x$ of Fig. 1. Fig. 3 is a plan view thereof.

Similar letters of reference will be used to designate the same parts wherever they are shown.

As shown in the drawings, the leading or material feature of my design consists of two vertical cylindrical columns a a , united at the top by an arched portion b , which is rounded, as shown, so that the arch appears as a continuation of the two columns. At the base the columns are joined by a horizontal por-

tion a' , branching from the flaring base a^2 , as indicated most clearly in Fig. 1. On the under side of the arch the parts are formed to leave a semicylindrical transverse opening c , and on either side of the arch disposed concentrically with such opening are provided cup-shaped caps d e . Cylindrical portions f f extend horizontally from the extremities of the cups d e , and cylindrical projections g g extend downward from said cylindrical portions f f , as indicated in Figs. 1 and 2, being pendent therefrom by the necks g g' of smaller diameter.

Having thus described my invention, what I claim as new, and desire to secure by Letters Patent, is—

The design for a motor-frame, as herein shown and described.

Chicago, April 5, 1899.

HENRY H. WAIT.
